UNITED STATES PATENT OFFICE.

FRANK S. INGOLDSBY AND JOSEPH R. BOWLING, OF ST. LOUIS, MISSOURI,
ASSIGNORS TO THE INGOLDSBY AUTOMATIC CAR COMPANY, OF ST. LOUIS,
MISSOURI, A CORPORATION OF WEST VIRGINIA.

DUMP-CAR.

SPECIFICATION forming part of Letters Patent No. 747,481, dated December 22, 1903.

Application filed August 25, 1902. Serial No. 120,922. (No model.)

To all whom it may concern:

Be it known that we, FRANK S. INGOLDSBY and JOSEPH R. BOWLING, citizens of the United States, residing at St. Louis, in the 5 State of Missouri, have invented a certain new and useful Improvement in Dump-Cars, of which the following is a full, clear, and exact description, reference being had to the accompanying drawings.

10 The object of this invention is to provide in a form which shall be very strong and efficient a dumping-car composed largely of sheet-steel and rolled forms embodying the dumping principles of what is known as the 15 "Ingoldsby dump-car," illustrated in Patents Nos. 551,319, 613,279, and 632,650, granted to Frank S. Ingoldsby December 10, 1895, November 1, 1898, and September 5, 1899, respectively.

20 The type of car illustrated in the patents referred to may be described briefly as having, in its preferable form, inclined end floors, a central longitudinal beam, dumping-doors between the central beam, and sides hinged 25 at the central beam and swinging downward to discharge the load, and interlocking hooks carried by the sides of the car and engaging with the hooks projecting from the doors to hold the latter in place, a hand or power operated lever to move the hooks to disengage 30 the doors, and suitable mechanism to elevate the doors after they are dropped.

The present invention is concerned with the central longitudinal beam, which is a 35 truss with a sheet-steel top arranged to itself constitute the upper chord, with the connections of such beam with the bolsters and the draft-beam, and with the brace-bar for preventing the spreading of the car sides at the 40 middle of the car.

In the drawings, Figure 1 is a side elevation of a little over half of a car embodying the present invention. Fig. 2 is a longitudinal section of such car from the other end, 45 the section being taken at one side of the center, as indicated by the line 2 2 of Fig. 3. Fig. 3 is an end view of the car, half of it being a vertical section. Fig. 4 is a plan of the car near one end, and Fig. 5 is a bottom plan 50 near the opposite end. Fig. 6 is a detail of

the bolster, being a vertical section taken between the bolster and the proximate end of the car. Figs. 7 and 8 are details of the braces and struts of the central truss. Fig. 9 is a longitudinal vertical section in the vicinity of the bolster, being on the line 9 9 of Fig. 6. Figs. 10 and 11 are vertical sections on the lines 10 10 and 11 11, respectively, of Fig. 9. Fig. 12 is a vertical central section through the bolster. Figs. 13 and 14 are fragmentary details illustrating modified forms of the upper plate of the central truss. Fig. 15 is a detail of the adjustable cross-tie bar. Fig. 16 is a cross-section on the line 16 16 of Fig. 15, and Fig. 17 is a perspective 65 view of the threaded extension of the tie-bar shown in Fig. 15. Fig. 18 is a detailed sectional view of one of the struts applied to the side of the car, a portion of said side being also shown in section.

70 Briefly, the car shown includes girder sides A, (composed of sheet-steel plates, with suitable chords a a' a'' and struts a^3 a^4 riveted to the plates,) inclined ends P, a central longitudinal beam, (composed of the upper chord B, braces and struts C and C', and lower chord L,) bolsters D, draft-beams E, upper and lower end sills S and S', side extension-sills S'', and braces S³, S⁴, K, and J, trap-doors F, filling the space between the central 80 beam and the sides of the car, elevating mechanism G for closing the doors, and locking mechanism H for retaining them closed. The main struts a^3 are of Z-bar section, which allows of their convenient riveting to the car 85 side.

The mechanism shown for retaining the doors closed consists of beams h^2 , projecting from beneath the doors, hooks H on the side of the car interlocking therewith and shiftable by suitable means, as the links h and the lever h' . This retaining mechanism is fully shown in the prior patents hereinbefore referred to. The elevating mechanism, consisting of toggle-joints G, having flexible members connecting the knuckles thereof with rotatable shafts g , which may be rotated by suitable means, as the geared diagonal shaft g' and the crank g^2 , pivoted therewith, is 90 shown, described, and claimed in application, 95 100

Serial No. 51,656, filed by Frank S. Ingoldsby, March 18, 1901, and will not be herein more specifically described. When the lever h^1 is thrown to disengage the doors, it operates on the inclined end of a bar h^3 to disengage the raising-crank g^2 . This also has been fully set out in the prior patents.

We will now describe the central longitudinal truss, wherein our invention largely consists. The upper chord of this truss is a sheet-metal member B, in the form of an inverted V. This member may be made of one plate bent on its longitudinal medial line, as shown in most of the figures, or of two plates secured together by an outside angle b^1 , riveted thereto, as shown in Fig. 13, or an inside angle b^2 , riveted thereto, as shown in Fig. 14. In any event it is one rigid member, and we shall speak of it as a "plate" irrespective of the number of pieces of which it is composed.

The plate B (which may be composed of as many longitudinal sheets as desired) is braced on its under side by members C C' C², riveted to it, and is thus enabled to itself constitute the upper chord or compression member of the truss. Of these members the braces C are of the form indicated in Fig. 7 and are employed at points where the toggle-raising members G are located. The members C' form both braces and struts and the members C² simply braces. Each of these members carry door-hinges.

In the brace C, Fig. 7, there are two pairs of upright angle-bars c^3 c^3 , riveted at their upper ends c^4 to the plate B and at their lower ends to the malleable castings c^5 . These latter are braced by the angle cross-bar c^6 , riveted to each of them, and by the diagonal angle-bars c^7 c^7 , riveted to the castings and to the bars c^3 . A horizontal plate c^8 extends across this brace between the two members of each pair of uprights, being riveted to them. Outside of the members c^3 are the malleable castings c^9 c^9 , riveted to each of these members, to the plate c^8 , and also to the top plate at c^{11} .

In the struts C', Fig. 8, the vertical members may be made in one piece c^{13} , bent into a U shape and at its lower ends secured to the malleable castings c^{15} . The angle-braces c^6 c^7 c^7 and plate c^8 are the same as in Fig. 7. The malleable castings c^{19} stand outside of the vertical members c^{13} and are riveted thereto and to the top plate.

In each of the malleable castings c^9 and c^{19} there are formed holes c^{21} for the hinge-pins of the door-beams h^2 . The casting c^9 has a bearing c^{22} for the toggle-operating shaft g , which is shown as tubular. The casting c^5 has an eye c^{23} for the pin of the lower toggle member. The castings c^{15} carry bumpers c^{24} for the impingement of the floor-beams h^2 and carry grooves c^{25} for the reception of tie-rods constituting the lower chord. It will be seen that these vertical struts and braces, being composed simply of plates, an-

gle-bars, malleable castings, and rivets, will be as light as is consistent with strength, while being cheap in construction.

70

At its ends the longitudinal plate B, constituting the upper chord, is secured directly to the bolsters. The bolster is of the same general form as that shown in Patent No. 694,385 for a bolster granted to us March 4, 1902. It consists, briefly, of a center casting d , a channel-shaped compression member d' , extending beneath the center casting and inclining upward on either side to the side of the car, and the tension-strap d^2 , passing over the top of the casting and inclining downward and riveted at its ends to the compression member through intermediate filling-blocks d^3 . Between the tension and compression members are vertical braces d^4 and diagonal braces d^5 and diagonal tension-rods d^6 , held together by the bolts d^7 . Diagonal I-beams J , extending from the sides of the car to the outer ends of the draft-beams, pass intermediate through the vertical braces d^4 and are secured thereto. In the present invention, however, the bolster is made much higher at its center than shown in the prior patent referred to, and the top plate B extends directly across the center casting d , between it and the tension-strap d^2 , all three of these members being riveted together. The flanges at the upper side of the center casting d are inclined downward on each side, and the top plate B rests directly on these. Wedge-shaped filling-blocks d^8 rest on the top plate, and the strap d^2 passes over the filling-block and the top plate, and the same rivets d^9 secure all these parts together. The center casting preferably has cross-webs d^{11} and carries beneath the compression-channel a center bearing d^{12} .

100

The draft-beam consists of two vertical plates E, extending across the bolster and riveted to the outer sides of the central frame thereof and engaging the under side of the plate B and riveted thereto, as at e . These draft-plates are braced by suitable angle-strips e^1 e^2 , riveted to their inner sides on the inner side of the bolster, and angle-strips e^3 e^3 e^4 , riveted to their outer sides beyond the bolster. These draft-plates being rigidly held at their outer portions act also as cantilevers helping to sustain the central beam.

110

The flange of the center casting d of the bolster at its upper end extends toward the center of the car, as at d^{13} , and there are riveted to this extension and to the top plate and draft-plates a pair of diagonal braces K, leading to the inclined ends P of the car, being secured to the angle-bar p , riveted crosswise of said end.

120

The lower chord of the longitudinal truss consists of a pair of U-shaped tie-rods L, passing at their bends over saddles N and secured at their ends by the turnbuckles M and occupying intermediate the bottom grooves c^{25} of the struts C'. The saddle N is grooved to receive the tie-rod and rests at its inner edge

130

on the proximately vertical edge of the draft-plates E and on the contiguous flange of the center casting d of the bolster.

By the above-described construction the 5 draft-beams, the bolster, and the longitudinal beam are all very effectively bound together. At the same time the sides of the car are also rigidly bound through the bolster and the diagonal beams J, so that the 10 tugging and buffing strains are efficiently carried from one draft-beam to the other. The construction avoids the necessity of upper chords in addition to the inclined upper plate, which must be employed to shed the load, and 15 the arrangement of longitudinal tie-rods with their turnbuckles allows adjustment, so that these tie-rods shall bear their proper proportion of the strain.

At the center of the car the sides are braced 20 by the cross-plates R in an inverted-V shape. To prevent the sides near the middle of the car from bowing out at their upper ends, we provide a cross-tie. (Illustrated in Figs. 15, 16, and 17.) This consists of an angle-bar Q, to 25 each end of which is bolted an extension-bar q, as by the bolts q'. This extension-bar has a threaded shank q², adapted to extend through an opening in the side of the car and receive on its end a nut q³. 30 When in place, the nuts q³ thus hold the car sides from bowing outward. The particular advantage of this construction is, first, that it allows the parts to be very conveniently placed in the car, the extensions q being first placed and then the bar Q bolted to them and then the nuts tightened up, and, second, it furnishes a very convenient method for drawing in the sides of the car if they should have become bowed out when the bar 35 Q is not present. Thus the extensions q may have their shanks put through the openings in the bent car side and bolted to the bar Q and thereafter, the nuts q³ being tightened up, operate to force in the sides of the car to 40 their proper position. A considerable displacement of the sides can be rectified in this manner.

Having described our invention, we claim—

1. In a dump-car, a central longitudinal 50 truss having an upper and a lower chord, the upper chord being a sheet-metal plate of an inverted-V shape.

2. In a dump-car, a center truss having an upper and a lower chord, the upper chord constructed of an inverted-V-shaped longitudinal sheet-metal member braced by struts beneath and riveted to it.

3. In a dump-car, the combination of a pair 55 of bolsters each having a center frame therein and a central longitudinal beam having an upper metal plate extending across the bolsters and secured to them and to the center frames.

4. In a dump-car, a pair of bolsters each 60 having a center frame, and a central longitudinal beam having an upper metal ridge-plate riveted to the bolsters and to said frames.

5. In a dump-car, a central longitudinal truss whose upper chord is an inverted-V-shaped metal member, whose lower chords are 70 tension-rods, and struts between said chords.

6. In a dump-car, a central longitudinal truss composed of an upper chord consisting of an inverted-V-shaped metal member, struts composed of angle-irons, and lower chords 75 composed of tension-rods, with means for adjusting the tension of the same.

7. In a dump-car, a central longitudinal truss whose upper chord is an inverted-V-shaped sheet-metal member, whose struts are 80 composed of angle-irons and castings riveted together, and whose lower chords are tension-rods and turnbuckles.

8. In a dump-car, a longitudinal beam having an upper chord consisting of a sheet- 85 metal plate inclined downwardly on opposite sides, combined with struts beneath said plate, each including a pair of uprights riveted to the plate, and a pair of filling-blocks outside of the uprights riveted to the sides 90 of the uprights and to the plate, and separate castings at the foot of said uprights riveted thereto, and braces riveted to said foot-castings.

9. In a dump-car, a central longitudinal 95 truss, the upper chord of which is an inverted-V-shaped plate, and the lower member of which comprises a pair of U-shaped tie-rods adjustably connected together.

10. In a dump-car, a central longitudinal 100 truss, the upper chord of which is an inverted-V-shaped plate, struts depending from said plate and provided with seats, and a lower chord consisting of tie-rods resting in said seats and adjustably connected together. 105

11. In a dump-car, a central longitudinal truss having a ridge-plate of inverted-V form, struts and tie-rods, combined with a bolster to which said upper plate is secured and around the outer side of which said tie-rods pass. 110

12. In a dump-car, the combination, with a bolster having a center frame and a tension-strap extending over the top thereof, of a central longitudinal beam having a top sheet-metal plate extending between the center 115 frame of the bolster and the tension-strap thereof.

13. In a dump-car, the combination of a bolster having a center frame and a tension-strap extending across the top thereof, a longitudinal beam having a sheet-metal plate 120 extending across the center frame of the bolster between it and the tension-strap, and rivets passing through the tension-strap, the plate and the center frame and holding said 125 three parts together.

14. In a dump-car, the combination of a bolster, a central beam having an upper plate riveted to the bolster, and a draft-beam having plates riveted to the bolster and to said 130 upper plate.

15. In a car, the combination of an inverted-V-shaped longitudinal plate, a bolster, and a draft-beam, the longitudinal plate and the

- draft-beam being secured to the bolster and to each other.
16. In a car, the combination of a bolster having a central frame, a longitudinal plate, a draft-beam consisting of vertical plates, means for securing the longitudinal plate to the central frame of the bolster, means for securing the draft-beam plates to the central frame, said plates being extended beyond said bolster and secured to the longitudinal plate. 65
17. In a dump-car, the combination of a bolster, a longitudinal plate riveted thereto, a saddle on the outer side of the bolster, a longitudinal tie-rod occupying said saddle, and struts between the tie-rod and the plate. 70
18. The combination of a dump-car, of a center truss having a top cover-sheet which is its compression member, struts beneath said cover-sheet riveted to it, tie-rods which form the bottom tension member of said truss, and boltsters having central frames to which both the top sheet and the tie-rods are anchored. 75
19. In a dump-car, the combination of a central truss having a top cover-sheet as its compression member, vertical struts beneath the cover-sheet riveted to it, tie-rods extending beneath the vertical struts and bearing against them, a bolster to which the top sheet is riveted, and a saddle on the outer side of said bolster on which the tie-rods bear. 80
20. In a dump-car, the combination of a bolster, a central beam having an upper plate riveted to the bolster, a draft-beam having plates riveted to the bolster and to said upper plate, a saddle bearing against the outer side of said bolster and against said draft-plates, a tie-rod occupying said saddle, and struts between said tie-rod and said longitudinal plate. 85
21. In a dump-car, a bolster, a central truss having a longitudinal plate of inverted-V form riveted to the bolster, an inclined end floor for the car riveted to said longitudinal plate, and a brace-bar secured to the inclined floor and to the longitudinal plate and bolster. 90
22. In a dump-car, the combination of a bolster having a central frame, a pair of draft-plates passing through the bolster and riveted to the sides of said frame, a longitudinal beam having an upper metal plate riveted to said bolster, the draft-plates being riveted to the longitudinal plate, and suitable braces riveted to said draft-plates. 95
23. The combination with a pair of car sides having openings in them, of a cross-bar having a pair of extensions removably secured to it, said extensions having threaded shanks adapted to pass through the openings in the car sides, and nuts screwing onto said shanks. 100
24. A tie for holding together car sides consisting of an angle-bar and an extension-bar having an angle portion and a threaded shank, a bolt or pin for removably securing the angle portion to the tie-bar, and a nut screwing onto the threaded shank. 105
25. In a dump-car, a central longitudinal truss having upper and lower chords, the upper chord being a sheet-metal plate of an inverted-V shape which also acts as a beam between points of support. 110
26. In a car, the combination, with a hollow central longitudinal beam, of a brace therefor consisting of a central plate and angle members on opposite sides of the plate riveted to it and said beam. 115
27. The combination, with an inverted-V-shaped metal beam, of a brace beneath it and riveted to it, said brace consisting of pairs of metal members and an intermediate plate on opposite sides of which said members are riveted, said plate acting as a tie across the beam preventing it flattening out. 120
28. In a car, a brace consisting of a plate and pairs of metal members riveted thereto on opposite sides thereof, combined with dumping-doors hinged to opposite sides of said brace, said plate acting as a tie from hinge-pintle to hinge-pintle. 125
29. In a car, the combination of an inverted-V-shaped beam, a brace beneath the same consisting of a pair of vertical members the upper portions of which are riveted to the beam, a plate extending between and secured to said vertical members, and plates on opposite sides of said vertical members between said members and the beam. 130
30. In a car, the combination of an inverted-V-shaped beam, a brace beneath the same consisting of a pair of vertical members the upper portions of which are riveted to said beam, a plate extending between and secured to said vertical members, and plates on opposite sides of said vertical members riveted to the first-mentioned plate, and to said members and bridging the space between said members and the beam and riveted to the latter. 135
31. In a car, the combination of a bolster having a compression and a tension member, of a longitudinal sheet-metal inverted-V-shaped beam passing beneath and secured to the tension member. 140
